UNITED STATES PATENT OFFICE.

CHARLES S. SMITH, OF MILWAUKEE, WISCONSIN, ASSIGNOR TO A. O. SMITH CORPORATION, OF MILWAUKEE, WISCONSIN, A CORPORATION OF NEW YORK.

PRODUCTION OF INTEGRAL SIDE BARS AND SPRING HANGERS BY ELECTRIC WELDING.

Application filed February 8, 1924. Serial No. 691,337.

My invention relates to an improvement in integral side bars and spring hangers for automobile or other vehicle frames, it involving particularly the novel formation 5 of certain of the elements entering into the construction of the said integral structure, whereby such elements are formed and produced in a manner which will permit high capacity production of the integral structures economically and expeditiously by the 10 employment of an electric welding process.

The wholly new article produced by the practice of my invention is of superior construction, considered in its various aspects, 15 and of improved appearance, as will be related later on in this specification.

The features of novelty which reside in the invention will be pointed out in the appended claims.

20 In the drawing which accompanies this specification, and forms part thereof:

Figure 1 is a perspective view of one end of an integrally constituted side bar and spring hanger, constructed in accordance 25 with my invention.

Fig. 2 is a like view showing the separate elements and clearly delineating their peculiar formation, by means of which latter features the elements may be converted into 30 the integral structure, as illustrated in Fig. 1.

As before indicated, my invention relates to a new integrally formed side bar and spring hanger for an automobile or other 35 vehicle frame.

By way of introduction, it may be stated that in its substantial embodiment, the integral member comprises as one of its elements a pressed sheet steel side bar, drawn 40 from a blank of suitable contour so as to constitute a channel member, the bottom of which is formed by the vertically standing web of the side bar, and the sides by the marginal flanges, which extend laterally 45 therefrom. The respective widths of the vertical web and the lateral flanges will be such as to endow these elemental features of the construction of the side bar with capacity for resisting forces tending to the 50 deformation of the frame in which the side bars are incorporated, when the vehicle is heavily loaded or caused to encounter unfavorable road conditions while in operation. The end of the side bar is preferably cut square, so as to present an open channel

at the end of the bar. The other element comprised in the integral member will hereinafter be described.

Two of such side bars with their channels opposed, are connected in a permanent manner by means of a plural number of cross bars, preferably of a torsion resisting character. The extreme ends of the cross bars are entered in the channels of the side bars, to which they are united to constitute an assembled frame of such rigid structure that notwithstanding the loads which may be imposed upon the body of the vehicle supported upon the frame, or the adverse road conditions which may be encountered by the vehicle while the latter is in operation, the frame will maintain and preserve its original plane, and be substantially so free from deflection, as by weaving or twisting, that the negative effects of all vibrations upon the frame and its superstructure are wholly neutralized.

In automobile construction, the relative weight of the heavier sprung mass, when compared with that of the lighter unsprung mass, is greatly disproportionate. For instance, in an automobile having a net weight of 3000 pounds, the sprung mass, comprising, among other things, the frame, the body, and the power plant, may have a weight approximating 2250 pounds, while the weight of the unsprung mass, comprising, among other things, the springs, axles and wheels, may have a weight approximating 750 pounds. The gross weight of the sprung mass may be increased by as much as 1000 pounds, in the case of pleasure vehicles, when occupied; but in other types of vehicles, such as trucks, the gross weight of the sprung mass may be very much greater. Connection of the sprung mass with the unsprung mass, is made through the spring hangers attached to the side bars, such spring hangers being connected to the ends of the supporting springs, the latter being attached to the axles. Through the points of connection thus established, the excessive weight of the sprung mass finds its sole support.

The manner in which such connection between the two masses is effected, so that the superior weight may be properly supported, is therefore a matter of the utmost importance in automobile production. Heretofore, in effecting such connection, it has

been the practice to form the cast or forged spring hanger with a shank, or rearwardly extending tail piece, the length of which is approximately two-thirds of that of the 5 spring hanger. The shank of the spring hanger, after being machined to correct its dimensions, is placed in the channel of the side bar, with the three sides of the open channel closely embracing the corresponding 10 sides of the shank, and union of the parts is effected by a succession of riveting operations. A shoulder formed, by an expensive milling operation, at the transverse joining line of the shank of the spring 15 hanger with the head thereof, abuts the end of the side bar, when the parts are assembled, preparatory to the connecting operations.

In such operations, a hole is drilled vertically 20 through the flanges and the solid end of the shank contiguous to the shoulder, for the reception of a "king" rivet of appreciable size. The depth of solid metal to be drilled for the accommodation of this 25 rivet is determined by the over-all vertical dimensions of the end of the side bar through which the king rivet is passed. Usually, two holes are drilled through the web of the side bar and through the shank 30 of the spring hanger, for the reception of a like number of laterally disposed rivets. Three separate drilling and riveting operations, six in all, are therefore necessary to be performed in effecting the union between 35 the spring hanger and the end of the side bar to which it is connected.

As before indicated, it is of the greatest importance that the connection between the side bar and the spring hanger be perfectly 40 made, for the reason that the excessive weight carried upon such point of connection would contribute to disaster if the said connection be defective in any degree. Rigid inspection of the work is given, but 45 notwithstanding the exercise of the greatest care in assembling the spring hanger in its relation to the side bar, it frequently happens that a defective connection is found to exist upon such inspection. This condition necessitates the undoing of the work, as by cutting out the rivets, and the insertion of a new spring hanger by way of replacement. The corrective measures thus resorted to add greatly to the cost of 50 production, and despite the employment of skilled workmen, it seems impossible to eliminate the numerous defective productions. Another objection inherent to the older construction is the tendency of the connecting 55 rivets to work loose, and sometimes shear off, under the excessive strains and vibrations to which the vehicle is subjected when operated under conditions which are more than ordinarily severe.

60 The situation hereinbefore adverted to has

been the subject of much serious consideration by me, in my studies and experimentation conducted with a view to devising some means for obviating and overcoming the objections and difficulties inseparable from the 70 present practice of attaching the spring hangers to the side bars.

The present invention permits the attainment in a most perfect degree of the results so highly desired, and these are achieved in 75 a much more expeditious and economical manner than has been possible heretofore, and at the same time the product of my improved method possesses marked advantages in the way of increased strength and 80 improved appearance, as will be made clear later.

In carrying out my invention, I draw the channel side bar 10 as usual, preferably squaring the end so as to present a channel section 11, having a joining edge or line which lies in a plane transverse to the axis of the side bar. As to the second element of the integral member, instead of forging or casting the spring hanger 12, with the 90 usual shank, I form the rear end of the hanger with an abutting face, preferably as a short channel section 13 having a cross sectional formation which is the same as to its gauge as that of the channel side bar with 95 which it is brought into alignment. By forming the abutting channeled ends 11 and 13 of the two elements in the preferred manner described, so that they will have the same material formation, and consequently the 100 same exterior dimensions, so as to coincide when aligned, I am able to present an arrangement of the elements in which exactly similar thermal conditions can be produced. Hence, upon assembling the side bar 10 and 105 the spring hanger 12 with their channeled meeting ends abutting and aligned as at 14, an electric welding current applied to the parts at their meeting line will be subject to the same resistance and as a consequence the 110 abutting surfaces will be heated in exactly the same degree throughout, so that when a proper state of fusion of the metal of both elements in the region of such meeting line has been produced, the evenly fused surfaces 115 are amalgamated and constituted into an integral structure.

The slight endwise pressure exerted during the welding operation upon the parts when fused in the proper degree, extrudes 120 the fused metal laterally, so that a small but clearly perceptible flash is created, which latter is co-extensive in length with that of the whole of the fully exposed welding line. The presence of such flash is important, inasmuch as it constitutes a means whereby the thoroughness of the weld may be readily ascertained and determined by the merest casual inspection. Thus, the task of inspection is greatly simplified. Absence of the

flash from any part of the welding line, would be indicative of an imperfectly welded joint, while, as before stated, its existence throughout the welded line indicates a perfect result. As to the character of the weld, tests applied by me show that the structure is stronger in the perfectly welded region than is the metal in which the joint is formed.

10 The flash may be ground away so as to leave an entirely smooth surface, from which the welding line has entirely disappeared. This smooth exterior presents a desirable feature, and contributes greatly to the improved appearance of the side bar, inasmuch as the unsightly, projecting rivet heads incidental to the former practice are eliminated, and a graceful structure is produced. Possible dangers lurking in the older constructions in the liability of the rivets to become loose, are therefore completely eliminated by my present invention.

15 The forward end of the spring hanger 12 may be branched as at 15 and 16, and bored as at 17, to accommodate the end of the spring and its connections to the hanger.

20 Aside from the production of the stronger integral side bar and spring hanger in accordance with the present invention, the manufacturing cost is reduced to a point materially below that involved in the production of the older structures of this class. The omission of the shanks from the several spring hangers in a frame, together with their associated rivets, reduces the weight of the automobile by several pounds.

25 Although I have illustrated my invention in its preferred form in which the most certain and reliable desired results are attained with ease, it is obviously within the scope of such invention to vary its form from that shown. For instance, simple butt welding at the joining line of the end of the channel side bar and a spring hanger formed with a blunt or shouldered rear end is possible and may be resorted to in practice.

30 Having thus described my invention, what I claim and desire to secure by Letters Patent of the United States, is:

35 1. In an automobile frame, a channel side bar having an open end, and a spring hanger having forwardly extending spaced parallel ears for receiving between them the eye-end of a vehicle spring, the said spring hanger being provided back of said ears with a

transverse partition which serves to brace the ears in spaced relation, and being formed at its end in the rear of said partition with a channel coinciding with the adjacent end of the side bar, rear wall extensions of the 60 hanger aligned with and butt-welded to the ends of the walls of the channel side bar, the said partition serving to close the space defined by the rear wall extensions of the hanger and the walls of the channel side bar 65 in alignment therewith, except one side which is left open.

2. In an automobile frame, a laterally opening channel side bar cut square at its open end, and a spring hanger having forwardly extending spaced parallel ears for receiving between them the eye-end of a vehicle spring, the said spring hanger being provided back of the said ears with a transverse partition which serves to brace said 75 ears in spaced relation, and being formed at its end in the rear of the said partition with a channel coinciding with the adjacent end of the side bar, rear wall extensions of the hanger being cut square and aligned 80 with and butt-welded to the ends of the walls of the channel side bar, the said partition serving to close the space defined by the rear wall extensions of the hanger and the walls of the channel side bar in alignment therewith, except one side which opens 85 laterally.

3. In an automobile frame, a channel side bar having an open end, and a spring hanger 90 butt-welded thereto, the said spring hanger being formed at its outer end with means permitting a spring connection therewith and at its inner end with a channel coinciding with that of the adjacent end of the side bar, the said spring hanger being provided 95 intermediate its ends with a transverse partition which serves to brace the butt-welded meeting ends of the rear channel formation of the spring hanger and the adjacent channel formation of the side bar in spaced relation, the said transverse partition serving 100 also to close the space defined by the inner wall extensions of the hanger and the walls of the channel side bar in alignment therewith, except at one side which is left open. 105

In testimony whereof, I have signed my name at Milwaukee, this 4th day of February, 1924.

C. S. SMITH.
